(57) **CLAIM**

What is claimed is the ornamental design for a adapter housing, as shown and described.

DESCRIPTION

FIG. 1 is a perspective view of a adapter housing, showing the new design in a closed configuration;

FIG. 2 is a front elevational view thereof;

FIG. 3 is a rear elevational view thereof;

FIG. 4 is a top plan view thereof;

FIG. 5 is a bottom plan view thereof;

FIG. 6 is a left-side elevational view thereof;

FIG. 7 is a right-side elevational view thereof; and,

FIG. 8 is a perspective view thereof, illustrating the design in an open configuration.

The broken lines showing a logo design in FIGS. 1, 2 and 8 depict environmental matter, and form no part of the claimed design.
